UNITED STATES PATENT OFFICE.

THEODORE G. LEWIS, OF BUFFALO, NEW YORK, ASSIGNOR TO THE BUFFALO DENTAL MANUFACTURING COMPANY, OF SAME PLACE.

BLOWPIPE.

SPECIFICATION forming part of Letters Patent No. 633,859, dated September 26, 1899.

Application filed April 15, 1899. Serial No. 718,181. (Model.)

To all whom it may concern:

Be it known that I, THEODORE G. LEWIS, a citizen of the United States, residing at Buffalo, in the county of Erie and State of New York, have invented new and useful Improvements in Blowpipes, of which the following is a specification.

This invention relates to a blowpipe intended more especially for use in connection with gasolene-gas, although the same may be used with any other suitable gas, if desired.

The object of my invention is the production of a blowpipe in which the gas is concentrated and confined around the air-jet of the blowpipe in such a manner that the flame is not liable to be extinguished by an excessive blast.

In the accompanying drawings, Figure 1 is a side elevation of my improved blowpipe. Fig. 2 is a longitudinal section, on an enlarged scale, of the burner of the blowpipe. Figs. 3 and 4 are cross-sections in lines 3 3 and 4 4, Fig. 2. Fig. 5 is a longitudinal section similar to Fig. 2, showing a modified construction of the gas-confining hood.

Like letters of reference refer to like parts in the several figures.

A is the body or main gas-tube of the blowpipe, which has its rear end connected with a gasolene-gas generator or other source of supply by the usual hose, which is not shown in the drawings.

B is a hollow head or L-shaped casing or fitting having its inner branch secured to the front end of the main gas-tube A, preferably by a screw-threaded joint, as shown, and C is a hollow boss arranged on the upper side of said head and provided in its rear side with an opening or passage with which the usual air-blast pipe D of the blowpipe is connected. In practice this air-pipe is connected with a foot-blower or other air-forcing device or with a tank containing compressed air in a well-known manner.

E is a gas-delivery nozzle or tube secured at its inner end to the outer end of the head B, preferably by a screw-thread, and communicating with the chamber of the head, so as to receive the gas therefrom. This gas-nozzle is somewhat contracted at its outer end, as shown at e, and provided in its sides near its outer

end with an annular row of gas outlets or apertures e', through which the gas issues laterally from the nozzle.

F is an air tube or nozzle arranged centrally within the gas-delivery nozzle E and the outer branch of the head B and secured at its open inner end in an opening f, which communicates with the cavity of the hollow boss C, so that the air entering said cavity through the blast-pipe D passes into and through the air-tube F. The nipple or front end of the air-tube is tapered in the usual manner and extends a short distance beyond the surrounding gas-delivery nozzle E, as shown in Fig. 2. The air-tube is considerably smaller in diameter than the bore of the gas-nozzle to leave an annular space between these tubes for the passage of the gas. The contracted front end of the gas-nozzle is separated from the adjacent front portion of the air-tube by an annular gas-passage g.

H is an annular gathering hood or sleeve which surrounds the front portion of the gas-nozzle E and air-tube F and serves to confine the gas which issues from the lateral outlets e' of the gas-nozzle around the air-tube and directs such gas forwardly or toward the mouth of the gas-tube for sustaining the flame of the blowpipe. The rear portion of this confining-hood is fitted closely upon the gas-nozzle E and abuts at its rear end against the outer end of the head B, so as to close the rear end of the hood and prevent the entrance of the external air at this point. The hood is also closed on all sides for the same purpose. The bore of the hood is enlarged from a point in rear of the lateral gas-outlets e' of the gas-nozzle to the front end of the hood, as shown at h, to form an annular gas-space between said nozzle and the hood. This enlargement is preferably formed by flaring the bore of the hood, as shown in Fig. 2; but the enlargement may be of cylindrical form, if desired, as shown in Fig. 5. The hood extends a short distance beyond the gas-nozzle, as shown in Fig. 2.

When gas and air are supplied to the blowpipe, a portion of the gas entering the gas-delivery nozzle E issues forwardly in an annular sheet or column through the contracted space between the front end of the gas-nozzle

and the air-nozzle F, while the remaining portion of the gas passes laterally through the side opening e' of the gas-nozzle into the surrounding hood H, which confines the gas and deflects the same forwardly in proximity to the air-jet, producing an outer annular sheet of gas, which surrounds the inner sheet issuing at the front end of the gas-nozzle. These concentric envelopes of gas unite at or near the front end of the air-nozzle and commingle with the air-jet, producing a thorough mixture of gas and air, while the surrounding hood holds the gas in intimate relation to the air-jet, thereby supporting combustion and maintaining a flame under all conditions of air-pressure. It has been demonstrated that this improved construction of the burner prevents extinguishing of the flame by an excessive or over pressure of air, avoiding the blowing out of the flame at a critical moment and rendering the blowpipe very reliable in use. By closing the confining-hood at its rear end and on all sides the admission of external air to the hood is prevented, and the size and form of the flame can be regulated by the usual valve of the blowpipe without affecting the intensity of the flame which would result from supplying air to the hood.

I is the usual regulating-valve, arranged in the main gas-tube of the blowpipe, and j the projecting stem of the valve.

I claim as my invention—

1. In a burner for a blow-pipe, the combi-

nation with a casing having gas and air inlets or chambers, of a gas-delivery nozzle communicating with said gas-inlet and provided near its front end with lateral gas-outlets, an air tube or nozzle arranged within said gas-nozzle and communicating with the air-inlet of the burner-casing, and a confining-hood surrounding said gas-nozzle and separated therefrom by an intervening gas-space and closed at its rear end and on all sides, substantially as set forth.

2. In a burner for blowpipes, the combination with a casing having gas and air inlets or chambers, of a gas-delivery nozzle communicating with said gas-inlet and provided near its front end with lateral gas-outlets, an air tube or nozzle arranged within said gas-nozzle and communicating with the air-inlet of the burner-casing, and an imperforate confining-hood surrounding said gas-nozzle, the front portion of the bore of said hood being enlarged to form a gas-space between the gas-nozzle and the hood and the rear portion of the hood being closely fitted upon the gas-nozzle, whereby the rear portion of the hood is closed, substantially as set forth.

Witness my hand this 12th day of April, 1899.

THEODORE G. LEWIS.
